[57] **CLAIM**

The ornamental design for a fishline guide pipe, as shown and described.

DESCRIPTION

FIG. 1 is a left side elevational view of a fishing guide pipe showing our new design, the right side being a mirror image thereof;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view of a second embodiment, the right side being a mirror image thereof;

FIG. 7 is a top plan view thereof;

FIG. 8 is a bottom plan view thereof;

FIG. 9 is a front elevational view thereof; and,

FIG. 10 is a rear elevational view thereof.
